UNITED STATES PATENT OFFICE.

WILLIAM CAMPBELL CASE, OF DEXTER, NEW YORK.

EAVES TROUGH.

Application filed December 14, 1920. Serial No. 430,690.

To all whom it may concern:

Be it known that I, WILLIAM C. CASE, a citizen of the United States, residing at Dexter, in the county of Jefferson and State 5 of New York, have invented new and useful Improvements in Eaves Troughs, of which the following is a specification.

This invention relates to eaves troughs and has for its object the provision of a 10 device of this character which is formed in sections which are detachable even while the entire device is in position so that a damaged or worn out section may be removed and replaced without necessitating taking 15 down or replacing the entire trough.

An important object is the provision of a 20 device of this character which is lined with a water-proof building paper or similar fabric which is renewable in case of necessity.

Another object is the provision of a device 25 of this character having novel means whereby the different sections may be connected in such a way that they may be disengaged when required.

An additional object is the provision of a 30 trough of this character which will be simple and inexpensive, easy to assemble and disassemble, efficient in use, extremely durable in service, and a general improvement in the art.

With the above and other objects and advantages in view, the invention consists in the details of construction to be hereinafter 35 more fully described and claimed and illustrated in the accompanying drawings in which

Figure 1 is a side elevation of my trough, Figure 2 is a plan view,

40 Figure 3 is a longitudinal sectional view, Figure 4 is a cross sectional view,

Figure 5 is a plan view of two of the sections disengaged, and

45 Figure 6 is a perspective view of one of the stays.

Figure 7 is an enlarged detail view showing the construction and mounting of one of the stay members.

Referring more particularly to the drawings I have shown my trough as comprising 50 a plurality of sections 10 and 11, the former which is a closed end section and the latter of which is an intermediate section and open ended. Any number of sections 11 may naturally be used in the construction of a trough of the desired length

though only one section 11 is illustrated as being entirely sufficient to give a clear understanding of the invention.

The section 10 includes a metallic end 60 member 10^a of trough shape having one end open and its other end closed by a wall 12. The edges of this member 10^a are bent to form flanges 10^b. Disposed and suitably secured upon the inside of this member 10^a 65 is a lining 13 formed as a sheet of water proof building paper or the like, it being understood that anyone of a large number of materials of this character might be used, it being of course essential that the 70 material be such as not to corrode or be otherwise injuriously affected by water. This lining is of considerable greater length than the member 10^a so as to project beyond the open end thereof and has its edges 75 reinforced by inverted channel shaped metallic binding strips 14 bent closely into engagement with the lining and riveted thereonto. These reinforced edges of the lining are engaged beneath the flanges 10^b. 80

Each section 11 is formed as a short sheet metal trough member 11^a lined with building paper or the like 15 of greater length than the section so as to project considerably there beyond. This lining may be cemented or otherwise secured in place. The edges of the member 11^a are bent over to define flanges 11^b which are cut as shown at 85 16, to provide portions 17 and 19, the latter of which corresponds to the flanges 10^b of 90 the member 10^a. The lining 15 has its edges reinforced by inverted channel shaped metal strips 15^a riveted thereon, the ends of these reinforcements being engaged beneath the flange portions 17. These ends 95 and the flanges 17 are riveted to the member 11^a as shown at 18.

The sections 10 and 11 are assembled by slipping the reinforcing members 14 of the section 10 beneath the flanges 19 of the 100 section 11, after which the flange portions 19 are preferably bent into close engagement with the reinforced edges 14 engaged therebeneath so as to form a tight joint. The ends of the flange portions 17 at the cuts 105 16 therein serve as stops or abutments for the ends of the reinforced edges 14.

Subsequent sections 11 are added by slipping the flanges 19 thereof onto the reinforced edges 15^a of the previously assembled 110 section 11. As many sections 11 are added as necessary to bring the completed trough

up to the desired length. Owing to the provision of the lining it will be observed that the material of the trough itself will be protected against rust or other corrosion so that 5 the trough may be considered as practically indestructible. In the course of time it may be necessary or advisable to paint the lining with any suitable water-proofing compound so as to prolong its life. Whenever it is necessary 10 to replace any section this may be done by prying up the flanged portions 19 and sliding the sections along so that they no longer overlap whereupon the defective section may be removed and replaced. In 15 order to prevent outward expansion or inward buckling of the sides of the trough, I provide reinforcing means on each section. This reinforcing means consists of a transverse stay 20 formed from a strip of metal having its end portions bent downwardly, as shown at 21 and engaged against the outsides of the reinforcing strips 14 or 15^a as the case may be, these bent ends 21 terminating in upwardly bent portions 22 engaging 25 between the reinforcing strip and the lining as shown more clearly in Figure 7.

While I have shown and described the preferred embodiment of my invention, it is of course to be understood that I reserve the right 30 to make such changes in the form, construction, and arrangement of parts as will not depart from the spirit of the invention or the scope of the subjoined claims.

Having thus described my invention, I 35 claim:

1. An eaves trough comprising an end section and a plurality of intermediate sections detachably and telescopically engaged therewith and with one another, the end section 40 including a metallic trough having an end wall and formed at its edges with reflexly bent flanges, a lining of water proof fabric engaging the inner side of said trough and projecting beyond the open end thereof, 45 channel shaped binding strips secured upon

the edges of said lining engaged beneath said flanges, and each intermediate section consisting of a metallic trough member open at both ends and formed at its side edges with flanges, a water proof fabric lining within and projecting beyond one end of said second named trough member, and metallic channel shaped reinforcing strips secured upon the edges of said second named lining and secured beneath one end of said second named flanges, the projecting portion of said first named lining being engaged beneath said second named flanges.

2. An eaves trough comprising an end section and a plurality of intermediate sections 60 detachably and telescopically engaged therewith and with one another, the end section including a metallic trough having an end wall and formed at its edges with reflexly bent flanges, a lining of water proof fabric 65 engaging the inner side of said trough and projecting beyond the open end thereof, channel shaped binding strips secured upon the edges of said lining and engaged beneath said flanges, and each intermediate section 70 consisting of a metallic trough member open at both ends and formed at its side edges with flanges, a water proof fabric lining within and projecting beyond one end of said second named trough member, metallic 75 channel shaped reinforcing strips secured upon the edges of said second named lining and secured beneath one end of said second named flanges, the projecting portion of said first named lining being engaged beneath said second named flanges, and reinforcing means for each section consisting of a transverse stay formed from a strip of metal having downturned ends engaging exteriorly against the reinforcing strips of a 80 lining with said downturned ends terminating in upturned extremities engaging between the reinforcing strip and the lining.

In testimony whereof I affix my signature.

WILLIAM CAMPBELL CASE.
